UNITED STATES PATENT OFFICE.

ROBERT MATTHIES AND JOHN A. SHEPHERD, OF HAMMOND, INDIANA.

DUMP-BOX.

1,022,562.

Specification of Letters Patent.

Patented Apr. 9, 1912.

Application filed July 23, 1909. Serial No. 509,210.

To all whom it may concern:

Be it known that we, ROBERT MATTHIES and JOHN A. SHEPHERD, citizens of the United States, residing at Hammond, in the 5 county of Lake, State of Indiana, have invented a new and useful Dump-Box, of which the following is a specification.

Our invention relates to improvements in dumping wagons and consists in certain 10 novel features of construction, arrangement and combination of parts illustrated in the accompanying drawings, and hereinafter first fully described and then pointed out in the appended claims.

15 In the drawings, Figure 1 is a side elevation of a dumping wagon embodying our improvements. Fig. 2 is a bottom plan view of the same. Fig. 3 is a front elevation thereof. Fig. 4 is a transverse vertical section showing the doors on one side closed and those on the other side opened. Fig. 5 is a side elevation of a modified form of the 20 invention, and Fig. 6 is a front elevation of the same.

25 Our invention relates to the construction of the wagon box, and the box embodying our improvements may be used in connection with any form of running gear, for which reason the running gear is not illustrated in the drawings.

30 The sides and ends of the wagon box are formed of wood and connected by suitable angle irons for the sake of economy, but the entire body may be made of metal if so desired. The front end 1 may be constructed of a single board or a plurality of small boards, as may be preferred, and the sides are constructed of one or more boards 2, the ends of which project slightly beyond 35 the front end 1 and are joined thereto by angle irons 3 whereby a rigid and strong corner will be provided. At the rear end of the box we employ an angle iron 4 which extends around the sides and under the bottom, to which straps 5 are hinged at their 40 lower ends, as shown at 6, the said straps 5 being secured to transversely disposed boards 7 constituting an end gate which may be swung down to form an apron at 45 the bottom of the wagon box when the load is in boxes or sacks so as to permit the discharge of the load in the ordinary manner.

50 Arranged longitudinally within the wagon box and extending from end to end of the same is a T-iron sill 8, the rear end of which

is secured to the angle iron 4, and the front end of which is secured to an angle iron 9 constituting a cross sill and secured to a transverse bar 10 which in turn is secured to the lower edge of the front end of the 60 wagon box. Near the front and rear ends of the wagon box bolsters 11 are secured to this central longitudinal sill 8, and the ends of the said bolsters are suitably notched to fit upon standards or other parts of the 65 running gear. Upon the front side of the front bolster and the rear side of the rear bolster we secure supporting strips 12 upon which are secured the ends of longitudinally disposed boards 13 which constitute floor 70 sections for the wagon box at the ends of the same. Above these floor sections 13, and extending between the innermost edges of the same and the adjacent ends of the box, are removable guide boards, indicated at 14 75 in dotted lines in Fig. 1, which serve to give the wagon box a hopper-like formation so as to direct the contents of the box to the dumping doors in the operation of the invention. At intervals along the de- 80 pending portion of the T-shaped sill 8 we secure brackets 15 which carry a hinge shaft 16 upon which are fitted eyes 17 formed at the inner ends of brackets 18 secured to the under sides of the inner doors 19, the said 85 doors being thus hinged to the T-shaped sill.

85 The outer doors 20 are hinged to the sides of the wagon box by means of hinges 21 having their members secured to the wagon 90 box and the door respectively. The operating chains 22 have their inner or lower ends secured to the hinge shaft 16, or to collars 23 rigidly secured thereto, and extend outwardly therefrom under the doors and 95 through guides 24 on the undersides thereof, and then up along the sides of the wagon box and have their outer ends secured to the free ends of crank arms 25 rising from rock shafts 26 which are journaled upon the 100 sides of the wagon box and have their front ends provided with operating levers 27 which project inward in front of the front end of the box. It will readily be seen that if these operating levers be thrown upward and outward the crank arms 25 will 105 be swung outward and downward, whereupon the weight of the contents of the box will force the doors 19 and 20 to drop and permit the discharge of the said contents. 110

It will also be seen that the doors are arranged in two pairs, one on each side of the central longitudinal sill 8, and that a lever is provided to operate each pair of doors so that the doors may be operated simultaneously or independently, as may be desired.

The doors may be opened to their fullest extent so as to permit a quick discharge of the entire contents of the wagon box or they may be held at an intermediate position so that the load may be permitted to discharge in a trailing manner which will be found very advantageous in some cases, as for instance, to dispose road making material along the line of a road. In order to hold the doors at such an intermediate position we provide the dog 28 which is pivotally mounted on the front end of the wagon box near the side of the same, and has one end arranged to engage the notches of a quadrant or plate 29 arranged at the junction of the operating lever and the rock shaft, as shown most clearly in Fig. 3. The lever and rock shaft with the doors operated thereby may be held at any desired position by throwing the dog 28 into engagement with the proper notch in the plate or quadrant 29, as will be readily understood.

A foot rest 30 is provided at the front end of the wagon box and is secured to the same by brackets 31 which are fastened to the underside of the foot rest and to the lower edge of the front of the wagon box, as will be readily understood.

The seat consists of a board 32 secured upon the upper sides of angle irons or straps 33 having their upper horizontal portions rigidly secured to the under side of the seat and their front vertical portions hinged to the outer side of the front end 1 of the wagon box so that the seat may be turned forward and rest against the front end of the wagon box out of the way when the box is being loaded.

In Figs. 5 and 6 we have shown a modified form of the invention in which the rock shafts 26 are dispensed with and pulleys 34 are mounted on the sides of the box. The chains 35 which are secured to the longitudinal T-shaped sill, and pass under the doors in the same manner as in the arrangement shown in the other figures of the drawing, 55 pass over the said pulleys and are then carried to the front end of the wagon box where they are secured to operating levers 36 which are fulcrumed upon the sides of the box at the front end of the same and 60 are provided at their lower ends with notched segmental plates 37 engaged by pawls or dogs 38 pivoted upon the sides of the box in advance of the said notched plates, as clearly shown in Fig. 5. The operating levers 36 are formed into curved

arms 39 at an intermediate point of their length so as to present a curved guide or support upon which the chains 35 will ride in the operation of the device. As clearly shown in Figs. 5 and 6, the levers 36 are so disposed that their upper ends will be within convenient reach of the driver from the seat.

From the foregoing description, taken in connection with the accompanying drawings, it will be seen that we have provided a dumping wagon of a simple and strong construction which may be easily operated and by which the load will be efficiently held against premature discharge. When the doors are in their closed positions they fit up snugly against the lower edges of the sides and ends of the box and against the overhanging flanges of the central longitudinal T-shaped sill so that no open spaces will be left through which the contents of the box may be lost.

In order to prevent wear on the lower edges of the sides of the box by the contents of the same in the act of unloading, we provide wear plates 40 which are secured to the inner faces of the sides at the lower edges of the same, as clearly shown in Fig. 4. The greater portion of the weight of the load of the wagon box is borne by the T-shaped sill 8 so that the strain upon the sides and ends of the box is much less than in prior forms of dumping wagons.

In the usual use of the wagon, the guide boards 14 will be employed so as to direct the contents of the box toward the dumping doors and prevent the same accumulating in the front and rear corners, but if the box is to be used to transport articles in boxes or sacks or other forms of bundles, the said guide boards will be removed, and then when the box is to be unloaded the end gate 7 will be turned outward and downward and the load discharged over the same in the usual manner. This manner of using the box will be facilitated by making the flared portions of the sides removable.

Having thus described our invention, what we claim is:

A dumping wagon body, having an open bottom, a central sill T-shaped in cross section extending longitudinally thereof, brackets secured to the vertical terminal of said sill and longitudinally thereof, a longitudinally disposed hinge shaft carried in said bracket, a pair of longitudinal bottom doors upon each side of the sill, having one member of each pair hinged to said shaft at each side of the sill and the other members hinged to the lower edges of the sides of the wagon body, flexible elements attached at their inner ends to the shafts and extending under the doors, guides located under the doors and through which said flexible elements pass, a rock shaft journaled upon

each side of the body, a series of arms carried thereby and engaging the outer ends of the flexible elements, and a handle for each rock shaft operably connected, whereby the 5 flexible elements are drawn through the guides to close the doors.

In testimony that we claim the foregoing

as our own, we have hereto affixed our signatures in the presence of two witnesses.

ROBERT MATTHIES.
JOHN A. SHEPHERD.
